BOOT AND SHOE HOLDING TREE

Charles G. Hilton, Amarillo, Tex.

Application October 11, 1943, Serial No. 505,828

11 Claims. (Cl. 12—128.3)

The present invention relates to an improvement in boot and shoe trees, and is a continuation-in-part of my copending application Serial No. 422,572, filed December 11, 1941.

It is the tendency of boots and shoes that have been stretched or adjusted to the peculiarities of an individual's foot to return to their original shape unless retained in the stretched or adjusted position when not in use.

One of the objects of the present invention is to provide a boot or shoe tree that will hold the boot or shoe to which it is applied in conformity to the stretch or adjustment that has been made to meet the individual requirements of the wearer.

A further object of the invention is to provide a device that is adaptable for holding the toes of shoes or boots in a widened position; for holding the instep portion of the shoe in a widened position and for holding a lengthening strain on the shoe without a progressive widening action being present. The invention includes the use of bunion pieces which are insertable at various points on the device to take care of any irregularities of the foot by retaining such parts in stretched condition.

Another object of the present invention is to provide a boot or shoe holding device that is simple in construction, easy and positive in operation and economical to manufacture.

A preferred embodiment of the invention is shown in the accompanying drawings, in which:

Fig. 1 is a plan view of the device with dash lines indicating the toe stretching action;

Fig. 2 is a similar view, with parts broken away and in section to show details of construction;

Fig. 3 is a side elevation of the device, with dash lines indicating the movement of the stretching links, and a shoe shown in dot and dash outline;

Fig. 4 is a cross section on the line 4—4 of Fig. 1;

Fig. 5 is a longitudinal section on the line 5—5 of Fig. 1;

Fig. 6 is an exploded perspective view of the sliding guide members;

Fig. 7 is a perspective view of the wedge member, removed, which engages the sliding guide member;

Fig. 8 is an elevation of an instep stretcher removed from the device;

Fig. 9 is a plan view of the bunion piece removed from the device;

Fig. 10 is a side elevation thereof; and

Fig. 11 is a view of the link or tie member removed from the device.

Referring more particularly to the drawings, the numerals 1 and 2 designate a pair of stretching members arranged in complementary relation and preferably shaped to conform with the

toe portion of a shoe. The stretching members 1 and 2 have a pair of spaced holes 3 and 4 at each opposite end thereof in position to receive a connecting hook or link 5 (Fig. 11), which may be engaged selectively in either pair of holes. Thus the members 1 and 2 will be connected together at one end only thereof, the opposite end being free for expansion as indicated in full lines and in dash lines in Fig. 1. When the connecting hook or link 5 is engaged in the holes 3 the opposite end is free to be spread laterally, and likewise when the hook is engaged in the holes 4. If desired both ends may be left free so that the foot members may be urged outwardly freely to fit the shoe as desired.

Provision is made for spreading the members 1 and 2 relative to each other, for which purpose, each of the members 1 and 2 has a guide member 6 pivotally attached thereto by means of rivet 7. The guide members 6 are telescoped together, one being inverted relative to the other for longitudinal sliding interfitting relation, as shown in Figs. 2, 4 and 5. Each of the slide or guide members 6 has laterally disposed slots 8, 8', therein in position for transverse alignment to receive, for transverse sliding movement, a wedge 10. Slots 11 and 11' at the outer ends of the slots 8, 8', receive one of the out-turned ribs 9, 9' formed on the wedge 10, for longitudinal movement when the two members 6 are telescoped together. Therefore, the spreading or expanding action of the foot members is dependent upon the lateral sliding of the wedge 10 sliding within the overlapped lateral slots 8 and 8', while ribs 9, 9' engaging in slots 11, 11', prevent the sides of the wedge from moving laterally relative to the members 6, with which it is engaged.

The members 1 and 2 are preferably formed of pressed metal; however, they can be made of any suitable material. A tongue 12 on the member 2 engages in slot 13 so as to guide the members 1 and 2 to and from each other. The slot is of sufficient length to permit a relative pivotal movement when the link 5 is engaged in holes 3 or 4.

The wedge 10 has out-turned flanges 14 at the end thereof to prevent its disengagement from the sliding members 6 when in retracted position. When in retracted position a link 5' (Figs. 1 and 5) similar to the link 5, engaging in holes 15, may be used to lock the wedge 10 against longitudinal movement when it is desired to put a strain or lengthening action on the boot or shoe instead of a widening action.

55 The rear portion of the wedge 10 is provided with an upwardly extending portion 16 having a slot 17 which extends into the horizontal part of the wedge. A heel bar 18 is adapted to be inserted through slot 17 and for this purpose the slot 17 is of greater length than the width of

bar 18 and of less width than the width of the bar. This arrangement permits insertion of the bar 18 through the slot 17 and its adjustment by means of notches 19 in the edges of the bar. By turning the bar in aligned position with the wedge member, the two members may be interlocked in the adjusted relation. A toggle action, as indicated in Fig. 3, may then be obtained by pushing down the upstanding part 16.

The heel bar 18 may be used in the position shown in full lines in Fig. 5, or it may be reversed as shown by the dash lines therein. This reversibility permits use of the device in a shoe or boot with a high arch, such as a high heel shoe or a cowboy boot, and the toggle action is obtained in either position. The wedge and the sliding members have sufficient clearance to permit an up and down motion of the wedge member 10 as shown particularly in Fig. 3.

The members 1 and 2 are provided with rectangular recesses 20 in the sides thereof to hold bunion pieces 21 for applying localized stretching to the shoe as may be desired. Such recesses may be provided in the foot members, along the instep and in the heel portion of the device. While any form of bunion piece may be utilized, it is preferable to use one having an eccentric configuration such as shown at 21 in Fig. 9. When the recesses are punched from sheet metal the inturned edges will serve to grip the neck 22 of the bunion piece 21 as will be evident from an inspection of the heel portion disclosed in Fig. 5. Obviously, by providing the bunion pieces with square shanks to fit square or rectangular recesses, a turning motion is prevented.

The upper sides of the foot members 1 and 2 are provided with rectangular slots 24 to receive lugs 25 formed on an instep stretcher 23 to apply additional pressure to the instep of the boot or shoe. A shoulder 26 is formed on the instep stretcher 23 to bear against the upper portions of the foot members 1 and 2, as additional support therefor.

The notches 19 in the heel bar 18 lock in the upwardly extending portion 16, thus preventing a side-swinging motion of the heel bar on the wedge member 10 when strain is applied to them.

I claim:

1. A shoe holding device comprising a pair of stretching members, means connected with the members for causing lateral spreading movements thereof, a thrust member connected with said spreading means for operating the same, and a second thrust member extending lengthwise of the first mentioned thrust member, and means for detachably interconnecting the thrust members together.

2. A shoe holding device, comprising a pair of stretching members, and means for applying a spreading action to said members, said spreading means including guide members connected with the spreading members and extending transversely thereof in longitudinal overlapping relation, and means having slidable connection transversely of said guide members for causing lengthwise relative sliding movement thereof to adjust the stretching members toward and from each other.

3. A shoe holding device comprising a pair of stretching members, means pivotally connecting the members directly together at one end thereof for lateral swinging movement, and means for applying a spreading action to said members, said

spreading means including guide members connected with the stretching members and extending transversely thereof in longitudinal overlapping relation, and means having slidable relation transversely of said guide members for causing lengthwise movement thereof relative to each other.

4. A shoe holding device comprising a pair of elongated stretching members, said members having a pair of openings in each opposite end thereof, a link detachably and selectively engaged in the pair of openings at one end of said members and pivotally connecting the members together at said end, and means for applying a stretching action to said members.

5. A shoe holding device comprising a pair of elongated stretching members, said members having a pair of openings in each opposite end thereof, a link detachably and selectively engaged in the pair of openings at one end of said members and pivotally connecting the members together at said end, and wedging means intermediate the length of the members for applying a stretching action thereto.

6. A shoe holding device comprising a pair of stretching members, guide sections each connected with one of the stretching members, said guide sections having laterally overlapped portions, said overlapped portions having a guideway therein, and a wedge member engaging in said guideway to apply a spreading action to said stretching members.

7. A shoe holding device comprising a pair of stretching members, guide sections each pivoted to one of the stretching members, said guide sections having laterally overlapped portions, said overlapped portions having a slot therein, and a wedge member engaging in said slot to apply a spreading action to said stretching members.

8. In a shoe holding tree, a pair of complementary foot members, a guide including sections telescoped together and connected with the respective foot members, said guide having an elongated slot therein with offset slot portions at opposite ends of said slot, and a wedge slidably longitudinally in said slot and having offset flange portions at opposite edges thereof, engaging in the offset slot portions.

9. In a shoe holding tree, a pair of stretching members, means connecting the stretching members together, a wedge member having wedging engagement with the connecting means upon longitudinal movement of the wedge member, a heel piece connected with the wedge member, and means for locking the wedge member against longitudinal movement relative to the connecting means.

10. In a shoe holding tree, foot and heel stretching members having longitudinal shank portions, one of said portions having an upwardly extending end and having a slot therein, the other shank portion being of greater width than the slot and having serrated opposite edges, the last-mentioned shank portion extending into the slot.

11. In a shoe holding tree, foot and heel members having longitudinal shank portions, one of said shank portions having an upwardly extending end and having a slot therein, and the other shank portion extending into the slot and having means thereon of greater width than the slot for holding the shank portions in assembled relation.

CHARLES G. HILTON.
